CLAIM

The ornamental design for a spray cap for aerosol container, as shown and described.

DESCRIPTION

FIG. 1 is a perspective view of a spray cap according to my new design;

FIG. 2 is a front view of the spray cap of FIG. 1;

FIG. 3 is a right side view of the spray cap of FIG. 1;

FIG. 4 is a left side view of the spray cap of FIG. 1;

FIG. 5 is a back view of the spray cap of FIG. 1;

FIG. 6 is a top view of the spray cap of FIG. 1; and,

FIG. 7 is a perspective back view of the spray cap of FIG. 1.
